UNITED STATES PATENT OFFICE

2,419,270

PARALLEL SCREW CLAMP

John G. Linnartz, New York, N. Y.

Application July 7, 1944, Serial No. 543,778

2 Claims. (Cl. 144—301)

1

The present invention relates to new and useful improvements in clamps of the parallel jaw type, and has for its primary object to provide, in a manner as hereinafter set forth, a device of this character comprising a novel construction and arrangement whereby, after the jaws have been adjusted as desired, said device may be conveniently used with one hand, thus leaving the other hand free to be used for inserting and removing the pieces to be held.

Another very important object of the invention is to provide a parallel jaw clamp of the aforementioned character which embodies unique means for closing the jaws for firmly gripping the work.

Other objects of the invention are to provide an improved parallel jaw clamp which will be comparatively simple in construction, strong, durable, highly efficient and reliable in use, compact, light in weight and which may be manufactured at low cost.

All of the foregoing and still further objects and advantages of the invention will become apparent from a study of the following specification, taken in connection with the accompanying drawings wherein like characters of reference designate corresponding parts throughout the several views, and wherein:

Figure 1 is a view in side elevation of an improved parallel jaw clamp constructed in accordance with the present invention.

Figure 2 is a view principally in longitudinal section through the device.

Figures 3 and 4 are views in transverse section, taken substantially on the lines 3—3 and 4—4, 35 respectively, of Figure 1.

Figure 5 is a detail view in perspective of the movable jaw.

Figure 6 is a detail view in perspective of the stationary jaw.

Figure 7 is a detail view in perspective of the lever.

Referring now to the drawings in detail, it will be seen that the embodiment of the invention which has been illustrated comprises a pair of opposed, coacting, parallel stationary and movable jaws 1 and 2, respectively. Extending rearwardly from the stationary jaw 1 is an integral handle 3. As illustrated to advantage in Figure 6 of the drawings, the stationary jaw 1, at the point where it merges with the handle 3, has formed in its longitudinal side portions parallel recesses 4 defining therebetween a longitudinal apertured rib 5. An angular lever 6 straddles the rib 5 and is pivotally connected thereto at 7.

2

Adjusting screws 8 and 9 connect the jaws 1 and 2. The screw 8 is loosely and rotatably anchored at 10 in the stationary jaw 1 and threaded through an intermediate portion of the movable jaw 2. The screw 9 is threaded through the rear end portion of the movable jaw 2 and has one end rotatably anchored at 11 in the lever 6 at a point adjacent the pivot 7 thereof.

A compression coil spring 12 extends between the rear end portion of the lever 6 and the handle 3 for setting the jaws 1 and 2 on the work. A thumb screw 13 is threadedly mounted in the lever 6 and engageable with the handle 3 for positively setting the jaws 1 and 2 on the work.

15 It is thought that the manner in which the clamp functions will be readily apparent from a consideration of the foregoing. Briefly, the jaws 1 and 2 are initially adjusted as desired in the usual manner through the medium of the screws 3 and 9. While holding the device in one hand, the lever 6 is swung toward the handle 3 against the tension of the spring 12. With the other hand, the pieces to be held are inserted between the jaws 1 and 2. The lever 6 is then released and

20 under the influence of the coil spring 12 the members 9, 2 and 8 will be rocked relative to the stationary jaw 1 in a manner to firmly clamp the work between the jaws. As hereinbefore stated, a positive lock or set may be had by tightening the thumb screw 13. To release the work it is only necessary to move the lever 6 toward the handle 3 against the influence of the spring 12 with one hand and remove the work from between the jaws with the other hand.

25 It is believed that the many advantages of an improved parallel jaw clamp constructed in accordance with the present invention will be readily understood, and although a preferred embodiment of the device is as illustrated and described, it is to be understood that changes in the details of construction may be resorted to which will fall within the scope of the invention as claimed.

What is claimed is:

1. A clamp comprising a stationary jaw, a rigid handle in longitudinal alignment with said stationary jaw, an adjusting screw rotatably and loosely mounted in and extending perpendicularly through the stationary jaw, a movable jaw threadedly carried by the adjusting screw for movement toward or away from the stationary jaw, a lever pivoted at one of its ends to the stationary jaw near its junction with the handle, said lever having a socket intermediate its ends adjacent its pivot, an adjusting screw threadedly extending

3

through the movable jaw in spaced parallel relation to the first-mentioned adjusting screw, the point of the second-mentioned adjusting screw being seated in the socket, and a compression spring extending between the end of the handle and the end of the lever remote from the pivot whereby the clamp jaws will be advanced toward closed position under yielding pressure.

2. A clamp comprising a stationary jaw, a rigid handle in longitudinal alignment with said stationary jaw, an adjusting screw rotatably and loosely mounted in and extending perpendicularly through the stationary jaw, a movable jaw threadedly carried by the adjusting screw for movement toward or away from the stationary jaw, a lever pivoted at one of its ends to the stationary jaw near its junction with the handle, said lever having a socket intermediate its ends adjacent its pivot, an adjusting screw threadedly extending through the movable jaw in spaced parallel relation to the first-mentioned adjusting screw, the

point of the second-mentioned adjusting screw being seated in the socket, and a compression spring extending between the end of the handle and the end of the lever remote from the pivot whereby the clamp jaws will be advanced toward closed position under yielding pressure, and auxiliary means positively to urge the clamp jaws to closed position.

JOHN G. LINNARTZ.
